COMBINED DIAL AND HANDS FOR A TIMEPIECE

Frederick J. Wachter, 915 Lois Lane, Glenview, Ill.

Filed Dec. 3, 1962, Ser. No. 72,687

Term of patent 14 years

(Cl. D42—1)

Fig. 1

Fig. 2

FIGURE 1 is a plan view of a combined dial and hands for a timepiece embodying my new design.

FIGURE 2 is a side view thereof.

The essential features of my design reside in those portions shown in full lines.

I claim:

The ornamental design for a combined dial and hands for a timepiece, substantially as shown and described.
